UNITED STATES PATENT OFFICE.

JACOB JAMES ELLIOTT, OF BETHLEHEM, PENNSYLVANIA.

MILK-BOTTLE HOLDER.

Application filed August 13, 1923. Serial No. 657,221.

To all whom it may concern:

Be it known that I, JACOB JAMES ELLIOTT, a citizen of the United States, residing at Bethlehem, in the county of Northampton 5 and State of Pennsylvania, have invented a new and useful Milk-Bottle Holder, of which the following is a specification.

This invention relates to milk bottle holders of the type used for receiving milk 10 bottles delivered by the milkman.

The object of the invention is to provide a simply constructed, cheap and efficient device of this character to facilitate the delivery and collection of milk bottles and 15 which is designed to be secured to a suitable support and to hold the milk bottle in either upright or inverted position.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed without departing from the spirit of the invention.

In the accompanying drawings:—

Figure 1 represents a side elevation of a 25 milk bottle holder constructed in accordance with this invention shown applied with a bottle in upright position shown in dotted lines therein; and

Figure 2 is a front elevation of the holder 30 detached.

In the embodiment illustrated, the holder 1 is constructed of a single piece of heavy wire bent to form a plurality of coils 2 of uniform size, any desired number of which 35 may be employed, four being here shown, the lowermost of which merges into a smaller coil 3 designed to form a rest for the bottom of the bottle shown at B in dotted lines. This coil 3 terminates in a downwardly inclined arm 5 with a depending right angu-

lar loop or eye 7 formed thereon designed to rest flat against a supporting surface 10 and be secured by a suitable fastening here shown in the form of a screw 8.

The upper coil 2 merges into an upwardly inclined arm 4 having a depending right angular attaching eye 6 located in the same plane as the eye 7 and which is secured to the support 10 by a screw 8 or other suitable fastener. 50

In the use of the device it being applied as shown in Fig. 1, the milkman will deliver the bottles B in upright position into the holder the bottle passing down through the coils 2 with its bottom coming to rest on the smaller coil 3. These holders are preferably made of different sizes to fit either quart or pint bottles. 55

When the bottle has been emptied and washed it is placed in the holder in inverted position with the mouth of the bottle resting on the coil 3. In this position the bottle will drain and be more or less protected from the entrance of dirt, litter or rain. 60

Various changes in the form, shape, proportion and other minor details of construction may be made without departing from the principle or sacrificing any of the advantages of the claimed invention. 65

I claim:—

A milk bottle holder in the form of a unitary structure consisting of a single heavy wire bent to form a spiral, a plurality of the coils of which are of uniform size, the lowermost coil being smaller to form a rest for the bottle, and the terminal coils being equipped with attaching eyes. 70

In testimony that I claim the foregoing as my own, I have hereto affixed by signature in the presence of two witnesses. 75

JACOB JAMES ELLIOTT.

Witnesses:

CHARLES E. ELLIOTT,
PHILIP RICHTER.
